UNITED STATES PATENT OFFICE.

EGBERT E. MASTERS AND LAVIRGNE J. KIMBALL, OF SACRAMENTO, ASSIGNEES, BY DIRECT AND MESNE ASSIGNMENTS, TO SAID MASTERS, AND ELDEN R. BRUSH, OF OAKLAND, CALIFORNIA.

WINDOW-BEAD FASTENER.

SPECIFICATION forming part of Letters Patent No. 316,555, dated April 28, 1885.

Application filed January 25, 1884. (No model.)

To all whom it may concern:

Be it known that we, EGBERT E. MASTERS and LAVIRGNE J. KIMBALL, citizens of the United States, residing in the city and county 5 of Sacramento, State of California, have made and invented certain new and useful Improvements in Window-Sash-Stop Locks, of which the following is a specification.

Our invention has reference to devices for 10 fixing window-sashes in their frames, and has for its object the production of an improved means for securing the sash stops or strips that confine the window-sash in the frames.

The following description fully explains the 15 manner in which we proceed to construct, make, apply, and use our said improvements, the accompanying drawings being referred to by figures and letters.

In the said drawings, Figure 1 is a perspective view of a portion of a window frame and sashes with our fastenings applied to the stops and lower sash. Fig. 2 shows the locking device for the sash-stops, and Fig. 3 gives the parts of the lock in detail.

25 A B represent the parts of a window-frame; C C, the sashes, and D the stops that secure the sashes in the run of the window-frame, the upright strips that confine the sash in its frame having the locking-fastenings H I to secure them in place, and to also afford ready separation from the frame when the sash is to be taken out. The lock H is formed of two parts—one, h, being a flat plate with screw-holes to fix it in place upon the front of the

30 sash-stop, and a short turn-bolt, h', loosely fixed in a socket in the center to turn freely while confined to the plate. The outer end of the bolt has a flat head, h², for turning it, and to the inner end is fixed a cross-bar, h³, formed 40 of a thin metal piece with an incline or wedge-

like face on the edge next to the back of the plate h. The other part, h*, has holes for fastening-screws also, and is slotted for the end of the bolt and its projecting bar h³. Upon its back, at the side of the bolt-aperture, is an inclined surface, h⁵, with which the edge of the part h³ is brought in contact after passing through the slot and as the bolt is rotated. Such action draws the two plates toward each other and causes the stop to be firmly pressed against the frame and locked in place. The ends of the stop D are provided with a cap, L, having a short pin, m, projecting from the end. A socket for this pin on each stop is provided in the window-frame at the bottom 45 or sill portion, and in placing the stop this bottom fastening is first inserted into the frame, and the top end is then sprung into place. A single lock, H, is then sufficient to hold the stop and prevent it from springing out. For 50 a long stop, however, two of these locks may be used.

Having thus fully described our invention, what we claim, and desire to secure by Letters Patent, is—

65 The combination, with the window-frame and sash-stop, of the sockets in the frame, the caps L on the ends of the stops having pins m, and the locks H, consisting of the socket-plate h*, secured to the window-frame, and the 70 bolt h', with wedge-shaped projections h³, adapted to take into the socket-plate and secured to the sash-stop, substantially as herein described.
